UNITED STATES PATENT OFFICE.

BURTON NEAL, OF ST. LOUIS, AND GEORGE HOWARD HEEBRAND, OF KINLOCH,
MISSOURI.

DRIVING MECHANISM FOR PRODUCING GYRATORY MOTION.

1,423,871.

Specification of Letters Patent. Patented July 25, 1922.

Application filed January 18, 1922. Serial No. 530,089.

To all whom it may concern:

Be it known that we, BURTON NEAL and GEORGE H. HEEBRAND, citizens of the United States, residing in the city of St. Louis and in Kinloch, St. Louis County, respectively, and State of Missouri, have invented new and useful Improvements in Driving Mechanism for Producing Gyratory Motion, of which the following is a specification.

10 This invention relates to a novel driving mechanism for use in producing gyratory movement. It is particularly adapted for application to machines for sifting flour, wherein such a motion is utilized for causing 15 the travel of the stock over the various sieves, and in the drawing the invention is illustrated in connection with a plan-sifter type of machine.

The general object of the invention is to 20 provide a drive for producing a gyratory movement of a body, such as a sifting machine, which will be self-balancing from the start to the maximum number of revolutions provided for.

25 Stated more in detail, it is a principal object of the invention to provide a drive of the character indicated, in which the driving part of the mechanism shall always occupy a fixed or centered position, while 30 the driven part of the mechanism, including the body to which the gyratory motion is to be imparted, shall, in operation, be gradually thrown off center so that its central median line or axis shall travel in a circular 35 path. By this arrangement, the gyratory movement is initiated and maintained with the minimum of irregular motions or vibrations, thus minimizing, or practically eliminating all strain from this cause on the 40 building.

A further object of the invention is the provision of driving mechanism involving the use of pivoted weights for producing a concentric movement of the axis of the 45 driven body relative to the axis of the driving mechanism or shaft, and the provision of a compensating connection between the driving and driven mechanism whereby there shall be no relative displacement between the driving and driven mechanism.

With the above general objects in view, the invention comprises a pair of spring-controlled weighted members which are adapted to be thrown outward by centrifugal 55 force and are geared to move in unison, such

weighted members being pivotally mounted on the driven body eccentrically of the vertical axis thereof, and a movable member actuated by the weighted members and connected with the driven mechanism, whereby as the driven body assumes an eccentric path of movement under the action of the weights, the connection with the driving mechanism will be correspondingly moved in an opposite direction, thus maintaining the same relative position between the driving part of the mechanism and its connection with the driven part of the mechanism or machine at all times.

The invention is illustrated in the accompanying drawings in which—

Figure 1 is a view in side elevation of a multiple plan-sifter provided with our improved driving mechanism, the machine being at rest and the axis or driven shaft of the device being in line with the drive shaft;

Figure 2 is a similar view illustrating the relative position of the parts with the machine in motion, and showing particularly the eccentric relation of the driving shaft to the driven shaft;

Figure 3 is a broken sectional plan view taken through the drive shaft and illustrating the position of the weights of the driving mechanism before the machine has been placed in motion; and

Figure 4 is a similar view illustrating the position of the weights with the machine in motion, and also showing by dotted lines, the circle described by the axis or driven shaft of the machine.

Referring now to these drawings, the numeral 1 indicates generally, a multiple plan-sifter machine of the type described and illustrated in a prior patent to Burton Neal No. 1,368,826 dated February 15, 1921, said machine being suspended from its four corners, as usual with plan-sifter machines, by means of wooden rods 2. The machine, as shown, comprises two sections of sieves indicated by dotted lines at 3, and between these sections at the center of the machine, a vertical space 4 is provided through which extends a driven shaft 5. Mounted on the top and bottom of the machine centrally thereof, are castings 6, 7, respectively, which provide bearings for opposite ends of the driven shaft 5, the upper casting 6 preferably embodying a ball bearing 8 for the upper end of the shaft 5. Fixedly secured

105

thereof, are bearings for opposite ends of the driven shaft 5, the upper casting 6 preferably embodying a ball bearing 8 for the upper end of the shaft 5. Fixedly secured

110

on the top and bottom of the shaft 5 are plates 9 and 10 respectively. In Figures 3 and 4 we have shown the construction at the top of the machine in connection with the plate 9, and as the construction at the bottom of the machine in this regard is identical with that at the top, a description of the upper mechanism will suffice for both.

Referring to Figures 3 and 4, the numerals 11 and 12 indicate two corresponding arms, each of which is provided at its outer end with a weight 13. At its inner end each arm is provided with a circular portion 14, 14^a which is provided with gear teeth 15 which are in mesh with each other. The geared ends 14, 14^a are pivotally mounted at 16 on the plate 9. Mounted on the upper side of the plate 9 at what may be termed its inner extremity relative to the position of the weights shown in Figure 4, is a post 17 (Figures 1 and 2) through which slidably extends a rod 18, one end of which is pivotally connected at 19 to one of the geared ends, that indicated as 14, eccentrically to its pivot 16. Secured on the rod 18 intermediate its ends, is a fixed collar 20 between which and the post 17 is interposed a coil spring 21. Secured on the top of the gear head 14^a is a plate 22 (Figures 2, 3 and 4) to which is pivotally connected one end of a bar 23, the opposite end of which is pivotally connected at 24 to the outer end of a short arm 25, the inner end of which is pivotally mounted at 26 on the upper end 35 of the post 17.

Referring particularly to Figures 1 and 2, the numeral 27 indicates a drive shaft which is actuated by a pulley 28 driven by a belt 29 and, while it is not considered absolutely essential to do so, it is deemed advisable to interpose two universal connections 30 in the length of the drive shaft, to allow for any slight lateral movement of the drive shaft which may occur as the machine is being placed in operation. Mounted on the top of the bar 23 is a socket member 31 in which is fixedly secured the lower end of the drive shaft 27, thus when this drive shaft is rotated by pulley 20, the plate 9 and the weighted members mounted thereon, and the shaft 5, will be correspondingly rotated.

As stated above, the construction at the bottom of the machine, so far as the mounting of the weights is concerned, is exactly the same as that described with reference to the mechanism at the top of the machine, and for the sake of convenience, the corresponding parts have applied thereto, similar reference numerals provided with the index *a*. There is, of course, no driving mechanism at the bottom and the drive shaft is supplanted by a fixed pin 32 mounted on the bar 23^a which is received into a socket member 33 secured on the floor 34. This

socket member 33 is not a bearing in the true sense of the term, as the pin 32 has a considerable play therein, its sole purpose being to prevent the machine from being pushed off the center, which very frequently happens in this type of machine so that sometimes for an hour or more at a time, they will have a wobbly or uneven movement before settling to movement in the proper path.

In operation the drive shafts 27 being rotated to correspondingly rotate the plate 9, weighted arms 11, 12 and driven shaft 5, (and, of course, plate 10 and the corresponding parts connected therewith at the bottom of the machine), the weights 13 and 13^a, being eccentrically mounted by their arms on the plates 9 and 10, will be thrown gradually outward in the direction indicated by the arrows in Figure 3, the maximum movement of the weights being reached when their opposed ends come in contact, as indicated in Figure 4. As the weights move outward, the bar 23 carrying the socket member 31 to which the shaft 27 is secured, will be drawn out of line with the shaft 5 in the same direction as the weights 13, as the pivotal connection 22^a of the inner end of the arms 23 with the plate 22 on the reared head 14^a (Figure 3) is eccentric to the pivotal mounting 16 of said head on the plate 9. In this initial movement there may be a slight movement of the drive shaft 27 from the vertical, caused by said movement of the plate 23. However, as the movement of the weights and the corresponding movement of the socket member 31 immediately places the drive shaft 27 and driven shaft 5 out of line, the shaft 5 being not only rotated but caused to bodily travel in a circular path as indicated by the dotted lines in Figure 4, a corresponding movement is, of course, imparted to the plan-sifter 3. In practice, the circle described by the shaft 5 will gradually increase in diameter until the weights come in contact, or until the maximum speed of rotation provided for is reached. In the present instance, at the maximum speed of rotation and with the weights in contact, it is designed that the circle described by the shaft 5 shall be four inches in diameter. After the initial movement above described, the movement of the shaft 5 in one direction away from a vertical center, will be in exact proportion to the movement of the shaft 27 effected by the movement of the plate 23 in the opposite direction so that the shaft 27 will always have a fixed vertical axis or, if there is a slight deviation therefrom, it will rapidly center itself as soon as the circular movement of the shaft 5 begins, which follows immediately the beginning of rotation of the shaft 27.

By the arrangement above described, it

will be seen that the gyratory movement of the plan-sifter or other body 1 is produced gradually, the movement being increased as the weights gradually move toward their 5 extreme outer position, and the movement off-center of the shaft 5 in one direction being exactly proportional to the movement of the shaft 27 in an opposite direction; and as the plate 9 is carried by the shaft 5 so 10 that said plate and all the parts mounted thereon, including the bar 23 carrying the socket member 31, the latter would be moved off-center corresponding to the movement 15 of the shaft 5 were it not for the fact that the outward movement of the weighted arms 11, 12 causes the movement of the socket member 31 in the opposite direction, thus maintaining the alinement of said socket member with the shaft 27. At the bottom, 20 the same operation occurs with respect to the pin 32 which is moved by the plate 23^a so that it always practically centers in the socket 33. By this arrangement there is no sudden eccentric movement of the plan-sifter or other body 1 causing an enormous 25 strain to be exerted on the floor of the building, but owing to the compensating movement between the shaft 5 and the drive shaft 27, and the gradual eccentric relation effected 30 between the center of rotation of the weights and the center of rotation of the shaft 5, the machine is always self-balancing from the start of the operation until it has attained the maximum speed of rotation.

35 We claim:

1. Driving mechanism for producing a gyratory movement of a suspended body, comprising a driven shaft on which said body is rotatably mounted, a plate fixedly secured on the end of said shaft, weighted 40 arms pivotally mounted at one end on said plate eccentrically of said driven shaft and having geared relation at such pivoted ends, said weights being adapted to be thrown out 45 ward under the action of centrifugal force when said plate and driven shaft are rotated, a socket member movable by said arms simultaneously with and in the general direction of the movements of said weights, and a 50 vertically disposed drive shaft having a driving connection at its lower end with said socket member for imparting rotation to said plates and the parts connected with and mounted thereon.

55 2. In driving mechanism for producing gyratory movement of a suspended body, in combination with a driven shaft on which

said body is pivotally mounted, a drive shaft, a differential drive connection between said drive and driven shafts, weighted arms carried by said driven shaft and pivotally mounted eccentrically thereof, and operatively connected with said driving connection and operating by an outward movement under centrifugal force when said drive 60 shaft is rotated to produce a lateral movement of the driven shaft with respect to the driving shaft in one direction and a corresponding movement of the driving connection in the opposite direction. 65

3. In combination with a suspended body having a driven shaft pivotally mounted therein, weighted arms operatively mounted on said driven shaft and pivotally mounted eccentrically thereof, whereby when said 70 driven shaft is rotated, the outward movement of the weighted arms under centrifugal action will tend to change the center of rotation of said driven shaft and cause it to travel in a circular path, a driving shaft for 75 rotating said driven shaft and a driving connection between said driving and driven shafts movable by said weights in one direction to an amount proportional to the movement of the driven shaft in an opposite direction. 80

4. Driving mechanism for producing gyratory movement of a suspended body, comprising a driven shaft on which said body is pivotally mounted, a plate fixedly secured on 90 one end of said driven shaft, arms pivotally mounted on said plate eccentrically of said driven shaft and having geared relation at their inner ends, a spring for controlling the movement of said arms about their pivots, a 95 movable member pivotally connected at one end to one of said arms beyond the pivotal connection thereof and at its other end being pivotally connected to said plate, and a drive shaft secured at one end to said movable 100 member to normally align with said driven shaft whereby in the rotation of the drive shaft the weighted arms will move outward and cause said driven shaft to be moved out of alinement with said drive shaft and the 105 said movable member will be moved in an opposite direction to said driven shaft and proportional to the movement thereof to maintain a substantially immovable point of connection with said drive shaft. 110

In testimony whereof we have hereunto set our hands.

BURTON NEAL.
GEORGE HOWARD HEBEBRAND.
